UNITED STATES PATENT OFFICE

158,962

CANASTA BOARD

Richard Jacob, Detroit, Mich.

Application October 22, 1949, Serial No. 5,661

Term of patent 3½ years

(Cl. D34—5)

To all whom it may concern:

Be it known that I, Richard Jacob, a citizen of the United States, residing at Detroit, in the county of Wayne and State of Michigan, have invented a new, original, and ornamental Design for a Canasta Board, for which the following is a specification, reference being had to the accompanying drawings, forming part thereof, in which:

Fig. 1 is a perspective view of a Canasta board, showing my new design.

Fig. 2 is a plan view thereof upon a larger scale.

Fig. 3 is a front elevational view thereof; and

Fig. 4 is a partial sectional view thereof taken from the left of Fig. 2.

I claim:

The ornamental design for a Canasta board, substantially as shown.

RICHARD JACOB.
